REVERSIBLE BUCKLE

Samuel Hornreich, New York, N. Y.

Application June 19, 1952, Serial No. 294,443

4 Claims. (Cl. 24—178)

1

This invention relates to new and useful improvements in reversible belts and reversible belt buckles.

More particularly, the present invention proposes the construction of an improved buckle which can be used with a belt having two sides each adapted for wearing outwardly disposed to permit the belt to be reversed simply by turning over the buckle and the belt strap.

Another object of the present invention proposes forming the buckle so that the belt can be reversed without unfastening the belt from the buckle.

Still further, the present invention proposes constructing the buckle with a tongue fastened to a tongue pivoting bar and fastening the belt to this bar so that an attractive, reversible belt is provided easy to use and economical to make.

As a further object, the present invention proposes arranging the tongue pivoting bar so that a belt can be swivelly fastened to it for reversing the belt merely by twisting it on the swivel.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the reversible belt and reversible belt buckle of the present invention.

Fig. 2 is a side view of the buckle and a part of the belt showing one side of the belt.

Fig. 3 is a view similar to Fig. 2 but with the belt and buckle turned over and showing the other side of the belt.

Fig. 4 is a view similar to Fig. 3 but showing the buckle pivoted around so the belt can be worn with its other side outwardly disposed.

Fig. 5 is a perspective view of the buckle alone in partly open position.

Fig. 6 is a sectional view taken on line 6—6 of Fig. 5 with the tongue shown in dot-dash lines 40 45 swung in its various positions.

Fig. 6A is a vertical sectional view taken on the line 6A—6A of Fig. 4.

Fig. 7 is a view similar to Fig. 2, but illustrating a modification of the present invention.

Fig. 8 is a view similar to Fig. 7 but showing the belt strap twisted on the swivelled member of the buckle in the process of reversing it.

Fig. 9 is a view similar to Fig. 5, but showing another modification of the invention.

2

Fig. 10 is a sectional view taken on the line 10—10 of Fig. 9.

Fig. 11 is a view similar to Fig. 2, but showing another modified form of the invention.

Fig. 12 is a sectional view taken on the line 12—12 of Fig. 11.

The reversible belt 15, in accordance with the first form of the invention illustrated in Figs. 1 to 6, inclusive, has a belt strap 16 and a reversible buckle 17.

Buckle 17 is comprised of a frame 18, a tongue 19 and a tongue pivoting bar 20 fixed to the tongue and pivotally connected with the frame, as will now be fully described.

The buckle frame 18 has closed sides 21 and 22 and closed ends 23 and 24 which preferably are identical as shown. The frame, as illustrated, is rectangular and has a central opening 25 between the sides and ends, the sides and ends framing the opening.

Tongue pivoting bar 20 is adapted to fit in opening 25 between the sides 21 and 22. Bar 20 is generally C-shaped in form, having arms 26 and 27 each fixed at one end to one end of the bar, the other end of each arm being pivotally connected with the buckle frame as by trunnions 28 and 29 on the arms 26 and 27 respectively being pivotally secured in sockets 30 provided in the sides 21 and 22 of the frame 18.

Tongue 19 is fixed at one end to the center of the bar 20 and has a free end extending and striking end 23 of the buckle frame when the bar 20 is pivoted on trunnions 28 and 29 in one direction and striking the other end 24 of the buckle frame when the bar 20 is pivoted in the opposite direction on the trunnions.

Belt strap 16 has two sides 31 and 32 each adapted for wearing outwardly disposed, and are stitched together by stitches 34. The strap 16 has an end loop portion 33 which is stitched between the two sides 31 and 32 by stitches 34a. This loop portion is formed with a tongue passage slot opening 35. End portion 33 is fastened to the tongue pivoting bar 20, the strap being put around the bar with tongue 19 struck through the slot opening 35.

The pivoting tongue bar 20 permits the tongue 19 to be easily and readily inserted in the retaining holes 36 of the belt strap (see Fig. 1). In addition, the pivoting tongue bar 20 permits the belt to be quickly and easily reversed. To wear the belt with the side 31 outwardly disposed, the buckle frame 18 is turned so that the free end of the tongue 19 is against end 23 of the buckle frame, as shown in Figs. 1 and 2. The tongue

19 may be provided with the usual tapered or bevelled edges 37 at its free end for ease of insertion through the belt strap holes 36 and for flat abutment against the frame ends.

To reverse the belt so that the side 32 may be worn outwardly disposed, the belt need only be turned over, as shown in Fig. 3 and the buckle frame 18 swung around until the free end of the tongue 19 is against the other end 24 of the buckle frame, as illustrated in Figs. 4 and 6A. Figs. 5 and 6 illustrate the freely pivotal action of the tongue pivoting bar and the tongue fixed thereto.

The modified form of the invention shown in Figs. 7 and 8 is characterized by the provision of a buckle frame 38 having two sides 39 and 40 and a closed end or front member 41. The sides each have one end joined to the front member and a central opening 42 lies between the sides and the front member. A tongue pivoting bar 43 has turned down end portions 44 pivotally connected to the free or rear ends 45 and 46 of the sides 39 and 40 respectively of the frame, as by being inserted through holes 47 in the sides and headed over. A tongue 43 fixed at one end to bar 43 has a free end 49 extending to and strikeable against the closed end 41 of the frame. A belt fastening bar 50 is pivotally fastened to the tongue pivoting bar, as by being swivelly pinned to the bar 43 by pin 51.

Belt strap 52 having end loop portion 53 is fastened to the fastening bar 50, a slotted opening 55, with extension slot 54 in one side of the end loop portion 53 is being provided for the bar 50 to be inserted through and then twisted crosswise of the opening 55.

In the modification illustrated in Figs. 9 and 10, a rectangular buckle frame 57 has two sides 58 and 59 and two ends 60 and 61 with an opening 62 therebetween. A tongue pivoting bar 63 is centrally located in the opening 62 between the ends of the frame.

Bar 63 has turned down end portions 64 and 65 pivotally secured in sockets 66 and 67 provided in the sides 58 and 59. A tongue 68 fixed at one end to the bar 63 has a free end 69 extending to and striking against either end 60 and 61 of the frame when the bar 63 is pivoted. Portions of the bar 63 adjacent the tongue 68 and between the sides 58 and 59 of the frame are long enough and so adapted for a belt strap to be secured thereto.

In Figs. 11 and 12, the reversible belt 70 is shown with an end slot 71 which will permit the tongue 72 to be rotated substantially 360° on trunnions 73 in the sockets 74 formed in the buckle 75 so that the bevelled edges 76 of the tongue 72 may engage either side of the striking side 77 of the buckle 75. In this form of the invention snap fasteners 78 are provided on the two sides of the slot 71 for engaging the buckle to the belt.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new and desire to secure by United States Letters Patent is:

1. A reversible buckle comprising a buckle frame having an opening therein, a C-shaped tongue bar having a pair of arms, a tongue extending from said bar in the direction of said arms and means pivotally securing the free ends of the arms of said tongue bar to the center of said frame whereby said bar is swingable within said opening, said tongue being more than half the length of the buckle frame.

2. The combination of claim 1 wherein said frame includes central sockets and said tongue bar includes trunnions retained in said sockets for reversible movement of the buckle.

3. A reversible belt buckle comprising a frame having two sides and two ends defining a rectangular opening, a tongue pivoting C-shaped bar mounted in said opening, said bar having parallel arms disposed within said opening adjacent respective sides of said frame, the free ends of said arms being pivotally secured to said sides at the center thereof whereby said bar is swingable within said opening, and a tongue extending from said bar in the direction of said arms and having a length greater than half the length of the buckle frame, whereby the end of the tongue is strikeable against one end of said frame in one position of said buckle and is strikeable against the other end of said frame when said buckle position is reversed.

4. A reversible belt buckle comprising a frame having two sides and two ends defining a rectangular opening, a tongue pivoting C-shaped bar mounted in said opening, said bar having parallel arms disposed within said opening adjacent respective sides of said frame, said frame sides being provided with centrally disposed sockets, said bar being provided with trunnions extending from the free ends of said arms and retained in said sockets whereby said bar is rotatable within said opening, and a tongue extending from said bar in the direction of said arms and having a length greater than half the length of the buckle frame whereby the end of the tongue is strikeable against one end of said frame in one position of said buckle and is strikeable against the other end of said frame when said buckle position is reversed.
